(57) CLAIM

The ornamental design for a bangle as shown and described.

DESCRIPTION

Reproduction 1.1 is a side elevation view of a bangle showing my new design;

Reproduction 1.2 is a perspective view thereof;

Reproduction 1.3 is an opposite side view thereof;

Reproduction 1.4 is another perspective view thereof; and Reproduction 1.5 is another side elevation view thereof, showing the bangle in an alternate state.

The portions shown in broken lines represent unclaimed subject matter only and form no part of the claimed design.
